INDIVIDUAL SERVICE CONTAINER

Isadore Schayer, Columbia, S. C.

Application January 12, 1939, Serial No. 250,633

5 Claims. (Cl. 215—63)

This invention relates to dispensing containers and closures therefor and more particularly to an improved container and closure.

In restaurants and other places where beverages are dispensed various problems are presented. Glasses are expensive, subject to breakage and require cleaning. The latter is not always thoroughly done. Soda straws add to the operating costs. Glasses and bottles must be stored on the premises. Beverage bottles may have contaminated lips.

One object of my invention is to provide an improved sealed package for the storing, shipping and convenient direct consumption therefrom of a beverage. The said container being formed with or without a handle and having a closure cap which after the initial opening thereof, may be conveniently and sanitarily opened and closed by the consumer, between draughts therefrom, retaining in a sanitary manner the unused portion of the beverage; or the closure cap of which at the option of the consumer may be pivotally swung downward to the side of the container for greater convenience in the consumption of the beverage.

A further object is to provide to the dealer an economical means of lessening his cost of drinking glasses, cost of cleaning and breakage and providing to the thrifty housewife and others a means whereby they may secure an extra supply of glassware at no appreciable extra expense.

Another object of my invention is to provide a closure cap for the aforesaid container with sides sufficient in length to protect that portion of the container which would be touched by the lips of the consumer in drinking therefrom, from the contamination of dirt and filth, thereby assuring hygienic protection.

Other objects and advantages of this invention will appear from the following description taken in connection with the accompanying drawings.

In the drawings wherein like numerals represent corresponding parts in the various figures—

Figure 1 illustrates in side elevation a container embodying features of this invention, portions shown partly in section.

Figure 2 is another view in elevation at right angles to that of Figure 1.

Figure 3 is a side elevation of another container incorporating features of this invention, but showing a variation in the method of securing the cap to the container.

Figure 4 shows a further variation in attaching the cap to the container.

Figure 5 shows in section a view through another variation in hinge.

Figure 6 is a top plan view of the device of Figures 1 and 2.

Figure 7 is a plan view of the device of Figure 5.

Figure 8 is an elevation showing a further variation in the hinge arrangement.

Considering the drawings in detail the preferred embodiment of the invention comprises a container or receptacle 10, made of glass or any other appropriate material and preferably formed into the shape of a glass or mug, a cap 11 removably sealing a liquid therein, which cap 11 may be initially removed from the top of the container by the usual means of cap opener, well known to the art. The said cap 11 remaining hinged to the container, after such operation, by the link 12, which link is pivotally secured at one end to the cap 11, and pivotally connected at the opposite end to the container. The cap is preferably made of metal but other suitable materials may be used.

The upper or open end of the container is preferably provided with an annular groove 13 and bead 14 forming an open end suitable for directly drinking a beverage from the container. When desired the container may be provided with a handle 15 for use in holding the container comfortably while drinking. This handle 15 has a central web 16 which is properly apertured at 17 for a purpose presently to be described.

In Figure 2 the loop of wire or link 12 secures the cap to the container by way of the pivotal hole or recess 17 in handle 15. This serves as one pivot or fulcrum for the link 12 when pivoting the cap to either an open or closed position, following the initial removal thereof, from the container top or upon the cap being in open position, the link 12 may be pivoted in the pivotal hole 17, projecting the closure cap from the open top of the said container on the arc of a circle having as the center point thereof, the point of pivotal connection between the link and container, the said arcuate projection terminating at the lower outer side of the said container. In Figure 4 the link is fastened to the container by means of a protuberance 18 extending outwardly from the wall of container 10 and apertured or recessed at 19 to pivotally receive the link 12. In Figure 3 the link is pivotally secured without providing a special handle or protuberance. In this case the container is formed with an annular groove or recess 20 in which is secured a wire 21 which latter is provided with a loop at 22.

Figure 4 shows a further variation in attaching the cap to the container.

The cap is preferably provided with an insert or lining 23 which assists in sealing the container. The side walls 24 of the cap are preferably made long so that they protect the bead and opening from contamination. Furthermore these walls may be indented or pinched as at 25 to yieldably engage the groove 13 of the glass.

A portion of cap 11 is formed into a hinge 26. This tubular hinge may be rolled clockwise as in Figures 5 and 7, or counterclockwise as in the other figures. In either case the hinge provides an elongated bearing for the link 12 and an extensive connection with the cap at 27. Where it is rolled counter-clockwise as in Figures 1 and 6, the hinge fits snugly to the cap as at 28, whereas in Figures 5 and 7 it is shown rolled in the opposite direction and being somewhat spaced from the cap at 29. This tubular bearing provides a long support 30 for the link. (See Fig. 2.) The bearing or hinge may be soldered, welded or otherwise treated to prevent unrolling, if necessary, but the material of which the cap is made is preferably sufficiently stiff to avoid the need of such treatment.

The central portion of the hinge material is formed into a tab or lug 31, and a perforation 32 is provided to receive the tab. The tab then projects to form a thumb lug or lever for pivoting the cap to either an open or a closed position, following the initial removal thereof, from the container top, with the link 12 serving as a fulcrum for the operation. The lug is stiff enough to accomplish this operation. The wire link 12 is also of stiff material so that it will not spread while being used as a fulcrum.

In Figures 5 and 7 the hinge is rolled clockwise and the lug or tab 33 extends through the slot 34.

In Figure 8 the hinge is formed in two parts 35 and 36 into which the ends 30 of the link 12 are received. The cap material is stiff enough to retain the parts in the relationship shown, or the tubular parts of the hinge can be welded or fastened together in any appropriate manner. The tab or lug 37 extends directly from the cap and retains its proper relation to the cap due to stiffness of material.

As previously described the link 12, shown in Figures 1, 2, 3 and 4, is pivotally connected to the container as indicated, respectively, by numerals 17, 22 and 19. Thus, it is readily apparent that at the option of the party using this invention the closure cap may be opened and closed between draughts therefrom, by manipulation of the thumb lug 31, or upon the closure cap 11, being in open position, the link 12, may be pivoted at the pivotal connection thereof, to the container projecting the closure cap from the open top of the said container along the arc of a circle formed by the pivotal movement of the link 12. The said arcuate movement of the said closure cap terminating at the lower outer side of the container, in which latter position the closure cap is conveniently placed so as not to interfere with the consumption of the beverage from the container.

While a preferred embodiment of this invention is shown and described, variations within the true spirit and scope of the same are to be determined by the appended claims.

What is claimed as new is:

1. A sealed shipping and storing package consisting of a container of glass-like form having a hollow body open at its top, said body being

5 of a size to be easily held by a person's hand and having a top defining bead whereby to permit easy drinking of a beverage directly therefrom, a removable sealing cap for the top of the said container having its walls flexibly engaging and extending below the said bead, a tubular bearing sleeve on the said cap, a thumb lug extending from the said bearing sleeve, the body of the said container having provided an annular groove, a looped member positioned in the said annular groove, a link member pivotally connected to the said looped member and the said link member pivotally engaged in the aforesaid tubular bearing sleeve, substantially as shown and described.

10 2. A sealed shipping and storing package consisting of a container of glass-like form having a hollow body open at its top, the said body having a top defining bead whereby to permit easy drinking of a beverage directly therefrom, a removable sealing cap for the top of the said container having its walls gripped about and extending below the said bead, a tubular bearing sleeve mounted on said cap, the said sleeve having mounted thereon an outwardly projecting thumb lug, a handle upon said container having a hole provided therein, a link member pivotally engaged in the said hole provided in the handle aforesaid, and the said link member pivotally connected to the said tubular bearing sleeve, substantially as shown and described.

15 3. A sealed shipping and storing package comprising a container of glass-like form having a hollow body open at its top, said body being of a size to be easily held by a person's hand and having a top defining bead whereby to permit easy drinking of a beverage directly therefrom, a removable sealing cap for said open top with its walls crimped upon the said bead, a tubular bearing sleeve on the said cap, a thumb lug extending from the said bearing sleeve, a protuberance formed integral with the body of the said container, the said protuberance having provided a hole therein, a link member pivotally engaged in the said hole and pivotally connected to the said tubular bearing sleeve, on the said cap, whereby the said cap after the initial removal thereof from the top of the said container may be pivoted on the said link member to either an open or a closed position and the said link member may be pivoted in such a manner as to pivot the said cap to the lower outer side of the said container.

20 4. An article of manufacture comprising a container of glass-like form having a hollow body open at its top, the said body having a top defining bead whereby to permit easy drinking of a beverage directly therefrom, a removable cap for the top of the said container having its walls gripped about said bead, a tubular bearing sleeve on the said cap, the said sleeve having provided an outwardly projecting thumb lug, a link member pivotally connected at the upper end thereof to the said bearing sleeve of the cap aforesaid, and means for pivotally connecting the said link member at the lower end thereof to the said container in such a manner that after the initial removal of the said cap from the top of the said container the said link member may be pivoted at the lower end thereof so as to project the said cap from the open top of the container to the lower outer side of the body of the said container.

25 5. A shipping and storing package comprising

a container having a hollow body open at its top, a cap for said open top, an operating member carried by said cap, a link member pivotally connected at one end thereof to the said cap, the body of the said container having a recess formed therein, means mounted in the said recess for pivotally connecting the other end of

the said link member to the said container in such a manner that the said cap may be raised to the top of the said container and lowered to the lower outer side of the body of the said container.

ISADORE SCHAYER.
